RECHARGING SYSTEM FOR RAPID-FIRING GUNS

Jacques Gustave Mejean, Geneva, Switzerland, assignor, by mesne assignments, to General Aircraft Equipment, Inc., South Norwalk, Conn., a corporation of Connecticut

Application June 6, 1941, Serial No. 396,919

8 Claims. (Cl. 89—1)

This invention relates to a system for recharging machine guns, such as the well-known .50 caliber Browning machine gun.

More particularly the present invention relates to a system for recharging machine guns and which effectively handles the initial peak load, requires a minimum of space and also a minimum quantity of compressed air for operation. To accomplish its purpose the system makes use of a telescopic arrangement which will be described in detail.

The principal object of the invention is the provision of a simple and effective system for recharging machine guns, light automatic cannon and the like.

Another object of the invention is the provision of such a system which is built on the telescopic principle with one piston cylinder disposed within another, the two pistons being actuated as a unit at the beginning of the recharging stroke to take care of the large initial load, and then, after the initial load has been overcome, the smaller piston being actuated to complete the recharging stroke.

The invention has for still a further object the provision of a system for the recharging of machine guns and the like, in which the consumption of compressed air is kept at a minimum.

These and other objects of the invention will be more apparent from the following description and claims when read in conjunction with the accompanying drawings in which:

Fig. 1 is a top view in section of the invention showing the system in its uncharged position.

Fig. 2 is a similar view, partly in section, and showing the system just after it has completed the recharging operation.

Fig. 3 is a top plan view, partly in section, showing the trip mechanism used with the invention.

Fig. 4 is a view on the line IV—IV of Fig. 3.

Fig. 5 is an exploded perspective view of the trip mechanism.

Fig. 6 is a view on the line VI—VI of Fig. 3.

Fig. 7 is a diagram showing the forces required in the operation of the system.

Machine guns are usually provided with a stud which projects laterally from the gun and which must be moved toward the back of the gun to recharge the same. The effort required to move this stud back is not equal and constant. There is a peak load at the beginning of the stroke. Moreover, there are other factors of importance which must be taken into account in any recharging system. One of these is the length of the system and the other is the amount of compressed air required for the operation of the system.

The invention which will now be described in greater detail, admirably and effectively takes these factors into account.

With particular reference to Figs. 1 and 2, the reference numeral 10 indicates a stud which projects laterally from the machine gun and which must be forcibly moved toward the rear of the machine gun (to the right of Fig. 1) to recharge the same. Secured to the side of the machine gun by clamps or other means (not shown) is a cylindrical casing 12 which houses the arrangement. This casing is provided with a longitudinal slot indicated at 14 into which the stud 10 projects.

15 The cylindrical casing 12 houses two telescoping cylindrical pistons, a larger one 16 and a smaller one 18. The front end of the larger telescoping member 16 is threaded to receive a cap member 20. The cap member has a central projecting boss 22 on which is secured a nut 24 having an annular groove 26 therein. Disposed between the nut 24 and the cap member 20 is a suitable packing ring 28. The cap member 20 and its projecting boss 22 are provided with a passage 23 for compressed air. The inner end of the passage is conical in form.

20 The front end of the casing 12 is provided with a cap member 30 which is threaded thereon. The cap member 30 is provided with an interior passage 32 leading to a source of compressed air (not shown).

The larger telescoping piston 16 is urged toward the front by means of the spring 34 which at one end abuts against the cap member 20 and at the other abuts against a ring stop member 36 rigidly secured to the inner wall of the cylindrical casing 12.

25 The smaller telescoping piston 18 is disposed within the larger piston 16. It is provided at its front end with a plug member 38 which likewise has an inwardly projecting boss 40 screw-threaded to receive a nut 42. The plug member at its largest diameter engages the inner wall of the larger piston 16 with a sliding fit. The nut 42 is provided with an annular groove 44. Between the nut 42 and the plug member 38 is a suitable packing ring 46. The smaller telescoping piston 18 is urged toward the front (that is to the left of Fig. 1) by means of a spring 48 which at its left end abuts the plug 38 and at its right end abuts against a stop ring 39 rigidly secured to the inner wall of the larger telescoping piston 16. The right or rear end of the telescoping piston 18 is closed by a plug 50. This plug carries a trip mechanism which will now be described. 30 From Figs. 3, 4 and 5 it will be seen that the

plug 50 has two rearwardly projecting spaced walls 52 and 54 which are adapted to receive therebetween a trip lever 56. The trip lever 56 is pivotally mounted on a pin 58 which passes through the openings 60 in the walls 52, 54. The trip lever 56 is in the form of a rocker lever, the shorter arm 62 of which is provided with a notch 64 adapted to engage the stud 10 which extends laterally from the machine gun. The longer arm 66 of the trip lever 56 has its movement in one direction limited by a stop pin 68 which passes through openings 70 in the walls 52 and 54.

Means are provided for releasably retaining the trip lever 56 in either of its two principal positions. Such means are comprised of a small pin 72 having one end rounded. The pin is disposed in an opening 74 in the wall 54 (see Fig. 5) and is greater in length than the thickness of the wall. The inner rounded end of the pin 72 is adapted to engage in either of two depressions 76 in the longer arm 66 of the trip lever 56. The pin is pressed inwardly by means of a leaf spring 78, the free end of which engages the same and the other end of which is provided with an opening through which the pin 68 passes. The head of pin 68 holds the spring against the wall 54. (See Fig. 4.) With the arrangement shown and described the trip lever will be retained in one or the other of its positions until it is forcibly moved through engagement with either the stop ring 36, or stop ring 80 secured to the inner wall of the cylindrical casing 12.

The device operates in the following manner: When the machine gun is ready for recharging, the recharging system is in the position disclosed in Fig. 1 with the stud 10 in position A. Compressed air is admitted through the passage 32 and enters the annular groove 26 in the nut 24, and acting on the walls of the groove thus moves both the larger and smaller telescoping pistons 16 and 18 as a unit rearwardly (to the right of Fig. 1). During this movement, the notch 62 of the trip lever 56 engages the stud 10 and moves it rearwardly. After the initial load required for loosening the packing member 28 and for moving the stud has been overcome, the compressed air which has entered the conical passage 23 acts against the walls of the annular groove 44 in the nut 42, and thus advances the smaller telescoping piston 18 alone to the right and this continues the rearward movement of the stud 10. When the stud 10 approaches the end B of its rearward path of travel, the lower arm 66 of the trip lever 56 strikes against the stop abutment 80. This causes the notch 62 of the trip lever 56 to slide under the stud 10 thus releasing the stud which returns to its position A. (See Fig. 2.)

During the rearwardly extending movement of the larger and smaller telescoping pistons 16 and 18, the springs 34 and 48 have become compressed. Diminishing the compressed air charge thus permits the springs 34 and 48 to return the two telescoping pistons 16 and 18 to their normal position shown in Fig. 1. Near the end of this return movement the lower arm 66 of the trip lever 56 strikes against the abutment 36 causing the arm 66 to move against the pin 68 and thus returning the trip lever 56 to a position where it is ready again to engage the stud 10.

The forces required for operation of the system are diagrammatically indicated on the chart, Fig. 7. When the pressure enters the cylindrical casing 12, it begins, as described, by pushing both telescoping pistons rearwardly and the resistance necessary to detach or loosen the packing mem-

ber 28 from the wall of the cylindrical casing is indicated in Fig. 7 by the reference character a. During that portion of the stroke o—m no other effort is exerted on the telescoping pistons. This is very important. It will be noted that only at point n will the telescoping pistons begin to push the stud 10 rearwardly. This stud offers a resistance which is indicated by the curve b. When the stud has arrived at the position o the larger telescoping piston has finished its stroke and the smaller telescoping piston then continues to go rearwardly alone.

To the resistances indicated the resistance of the springs 34 and 48 must be added. The resistance offered by the springs is shown by the curves c and d. The total resistance is indicated on the chart by the curve e. It is therefore necessary to calculate any piston in accordance with the curve f.

It should be apparent from the above that if the stud were acted on by only one piston, and that piston was required at the same time to loosen the packing member and move the stud, that such a single piston must, to accomplish the result, necessarily present double the surface, and would require about three times the amount of compressed air necessary for operation of the system described herein.

It is believed that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A device for recharging rapid firing guns comprising a cylinder mounted on the gun and having a slot therein adapted to receive a member projecting from the gun and whose movement is necessary to recharge the gun, telescoping pistons disposed within said cylinder, means in one end of the cylinder for admitting a medium under pressure to said pistons to move them first simultaneously and then to extend one with respect to the other, means carried by the end of one of the pistons for engaging the member projecting from the gun, said last-named means being movable into and out of member engaging position, means carried by said cylinder for disengaging said last named means from said member as the farthest extending piston reaches the end of its charging stroke, means within the cylinder for returning the pistons to telescoped position, and means on the cylinder for restoring said member engaging means to a position for reengaging said member.

2. A device for recharging machine guns and the like comprising a cylindrical casing mounted on the gun closed at both ends and having a longitudinal slot therein adapted to receive an element projecting from the gun and the movement of which is necessary for recharging the gun, a hollow cylindrical piston mounted in said casing, a second cylindrical piston telescopically disposed within the first piston, means at one end of the cylinder for admitting a medium under pressure to the one end of each of the pistons to move the pistons first simultaneously as a unit and then to extend the second piston with respect to the first, means carried by the end of said second piston and adapted to engage the element projecting from the gun, stop means

carried by said casing for disengaging said first-named means from said element as the second piston reaches the end of its path of travel in one direction, spring means within the cylinder for returning the pistons to their normal position, and means on the cylinder for restoring said element engaging means to a position for reengaging said stud.

3. A device for recharging rapid firing guns, comprising, a housing mounted on the gun, two telescoping pistons mounted within said housing, means within the housing for urging one of the pistons toward one end of said housing, means between said pistons for urging the other piston into telescoped position with respect to the first piston, means at one end of the housing to admit a medium under pressure to one end of said pistons first to move both pistons as a unit against the action of said first means, and subsequently to move the second piston to its extended position against the action of said second means, and means carried by the second piston for engaging and moving an element on said gun to recharge the gun.

4. A device for recharging rapid firing guns, comprising, a housing mounted on the gun, two telescoping pistons mounted within said housing, means within the housing for urging one of the pistons toward one end of said housing, means between the pistons for urging the other piston into telescoped position with respect to the first piston, means at one end of the housing to admit a medium under pressure to one end of said pistons first to move both pistons as a unit against the action of said first means, and subsequently to move the second piston to its extended position against the action of said second means, means carried by the second piston for engaging and moving an element on said gun to recharge the gun, and means carried by the housing for disengaging said last named means from said element as the second piston reaches the end of its stroke.

5. A device for recharging rapid firing guns, comprising, a housing mounted on the gun, two telescoping pistons mounted within said housing, means within the housing for urging one of the pistons toward one end of said housing, means between the pistons for urging the other piston into telescoped position with respect to the first piston, means at one end of the housing to admit a medium under pressure to one end of said pistons first to move both pistons as a unit against the action of said first means, and subsequently to move the second piston to its extended position against the action of said second means,

means carried by the second piston for engaging and moving an element on said gun to recharge the gun, means carried by the housing at one end thereto for disengaging said last named means from said element as the second piston reaches the end of its stroke, and means on the cylinder actuated by return movement of said pistons to their normal position for restoring said element engaging means to a position for again engaging the element.

6. A device for recharging rapid firing guns, comprising a cylinder mounted on the gun and having a slot therein adapted to receive a member projecting from the gun and whose movement is necessary to recharge the gun, telescoping pistons disposed within said cylinder, means at one end of the cylinder for admitting a medium under pressure to said pistons to move them first simultaneously and then to extend one with respect to the other, means carried by the end of one of the pistons for engaging the member projecting from the gun, said last named means comprising a pivoted double armed lever, one arm having a notch for engaging the member projecting from the gun, mechanism carried by the piston which supports said lever for limiting the pivotal movement of the lever in one direction, stop means disposed on the inner wall of the cylinder for engaging the other arm of said lever to pivot said lever at the end of the charging stroke to disengage the lever from the member projecting from said gun, spring means within the cylinder for returning the pistons to telescoped position and stop means also disposed on the inner wall of the cylinder to engage said other arm of said lever as the pistons return to their telescoped position to restore the lever to a position for reengaging said member.

7. In a device as defined in claim 2, the ends of the pistons to which the medium under pressure is admitted having circular grooves therein, and the first piston having a passage therein to enable the medium to reach the groove in the end of the second piston.

8. In a device as defined in claim 2, the ends of the pistons to which the medium under pressure is admitted having circular grooves therein, and the first piston having a passage therein to enable the medium to reach the groove in the end of the second piston, said last named ends of each piston being provided with packing rings respectively engaging the inner wall of the cylindrical casing and the inner wall of the first piston.

JACQUES GUSTAVE MEJEAN.
